[57] CLAIM

The ornamental design for a multi-function exercise machine, as shown and described.

DESCRIPTION

FIG. 1 is a right side elevational view of a multi-function exercise machine showing our new design;
FIG. 2 is a front elevational view thereof;
FIG. 3 is a rear elevational view thereof;
FIG. 4 is a top plan view thereof;
FIG. 5 is a left side elevational view thereof; and,
FIG. 6 is a perspective view thereof.
